SHAG RUG CARPET CLEANER HEAD

Sam G. Cox, P.O. Box 480, Hoyt Lakes, Minn. 55750

Filed Jan. 2, 1973, Ser. No. 320,559

Term of patent 14 years

Int. Cl. D7—05

U.S. Cl. D7—173

FIG. 1

FIG. 2

FIG. 4

FIG. 3

FIG. 6

FIG. 5

FIG. 1 is a perspective view of a shag rug carpet cleaner head embodying my invention;

FIG. 2 is a top plan view thereof;

FIG. 3 is a front elevational view thereof;

FIG. 4 is a side elevational view thereof;

FIG. 5 is a rear elevational view thereof; and

FIG. 6 is a bottom plan view thereof.

A side elevational view taken from the side opposite that shown in FIG. 4 is essentially a mirror image thereof.

I claim:

The ornamental design for a shag rug carpet cleaner head, as shown and described.
